UNITED STATES PATENT OFFICE.

WALTER W. FAWCETT, OF SHAKER HEIGHTS, OHIO, ASSIGNOR TO FULLER & SMITH, OF CLEVELAND, OHIO, A CORPORATION OF MICHIGAN.

DESIGN FOR A CARTON OR SIMILAR ARTICLE.

Application filed October 2, 1926. Serial No. 19,232. Term of patent 14 years.

To all whom it may concern:

Be it known that I, WALTER W. FAWCETT, a citizen of the United States, residing at Shaker Heights, in the county of Cuyahoga and State of Ohio, have invented a new, original, and ornamental Design for a Carton or Similar Article, of which the following is a specification, reference being had to the accompanying drawing, forming a part thereof.

In the drawing:

Fig. 1 is a perspective view of a carton or similar article showing my new design, in which the faces of the article are divided into contrasting triangular portions and the simi-

lar contrasting portions of three faces are merged to give a triangular effect in perspective at one corner of the article.

Fig. 2 is another perspective view, showing the article disposed in another position, and showing in connection with Fig. 1 that the triangular effects are obtained on diagonally opposite corners as well as on the individual faces of the article.

I claim:

The ornamental design for a carton or similar article substantially as shown and described.

In testimony whereof I affix my signature.

WALTER W. FAWCETT.
